UNITED STATES PATENT OFFICE

VICTOR S. THARP, OF ELMHURST, ILLINOIS, ASSIGNOR TO RESERVE HOLDING COMPANY, OF KANSAS CITY, MISSOURI, A CORPORATION OF DELAWARE

TELEPHONE SYSTEM

Application filed April 30, 1927, Serial No. 187,745. Renewed August 30, 1929.

The present invention relates in general to telephone systems, but is concerned more particularly with the method of handling toll calls to and from small exchanges.

5 In the present invention a small exchange located approximately half way between two larger exchanges is only connected to one of the larger exchanges by trunk lines comprising iron wires while the two larger exchanges are connected together by direct through toll lines. Connections from the small exchange, hereafter designated exchange No. 2, to the nearest large exchange, hereafter designated exchange No. 1, are 10 completed over the trunk lines connecting exchange No. 2 with exchange No. 1. In view of the fact that there are no direct trunk lines extending from the small exchange, or exchange No. 2, to the more distant large exchange, or exchange No. 3, connections between exchange No. 2 and exchange No. 3 must be set up or controlled over the trunk lines connecting the exchange No. 2 to the exchange No. 1 and then over the 15 through toll lines to exchange No. 3, although the through toll lines pass fairly close to the small exchange. The small exchange is not normally connected to the through toll lines because such connections, if permanently connected in bridge of the toll lines, 20 would greatly impair the transmission over such toll lines when they are used for connections between exchange No. 1 and exchange No. 2, and points beyond.

25 Accordingly, the main object of the invention may be said to consist in the provision of means for improving the toll transmission on toll connections between the small exchange and exchange No. 3. This is done by temporarily connecting the subscriber's lines at the small exchange to the through toll lines at a point where such toll lines pass near the small exchange. By this arrangement the length of wire in the talking circuits is greatly reduced and the quality of the circuits is correspondingly improved.

30 A feature of the invention relates to the novel circuit arrangement by means of which the connections to the through toll lines at

the small exchange are controlled at the will of the toll operator at exchange No. 1.

A further feature relates to the circuit arrangement by means of which night service can be furnished to a particular subscriber 55 whose line terminates in the small exchange when the operator at the small exchange has left her position after working hours.

Various other features will be pointed out in the detailed specification which follows. 60

Referring now to the drawing there is shown by means of the usual circuit diagrams sufficient of the apparatus used to enable the invention to be described and understood. 65

In the upper part of the drawing there are shown the conductors of one phantom and two physical through toll lines extending between two distant exchanges indicated as exchanges No. 1 and No. 3. These through toll lines terminate at one end in repeating coils and jacks such as repeating coil R and jack J in exchange No. 1 and at the other end in repeating coils and jacks such as repeating coil R² and jack J² in exchange No. 3. The 70 toll lines 1 and 2 are connected in phantom at exchanges No. 1 and No. 3, thereby providing the third toll line or toll line 3 between the exchanges. 75

Approximately half way between exchanges No. 1 and No. 2 the through toll lines pass at their nearest point within one thousand feet or so of a small rural exchange indicated as exchange No. 2. At this point a cable box, indicated by the dotted rectangle 80 in the upper and center portion of the drawing, is mounted on one of the poles of the toll line and a cable comprising the conductors 11 to 16, inclusive, connects the apparatus in the cable box with the apparatus in exchange No. 2. 85

In the lower left-hand part of the drawing there is shown the conductors of one phantom and two physical trunk lines extending between exchange No. 1 and exchange 90 No. 2. These trunk lines terminate at one end in repeating coils and jacks such as repeating coil R¹ and jack J¹ in exchange No. 1 and in the other end in repeating coils and jacks such as repeating coil R² and jack J⁴ in 100

exchange No. 2. The trunk lines 1 and 2 are made of iron wire and are connected in phantom at exchanges 1 and 2 thereby providing a third trunk line or trunk line No. 3 between the exchanges. Trunk line No. 3 is primarily for use as a dialing trunk and is equipped with a dial key K and a calling device CD by means of which the operator at exchange No. 1 may operate the connector C in exchange No. 2. Cord circuits (not shown) are also provided at exchanges No. 1 and No. 3 for completing or extending toll connections.

In exchange No. 2 conductors 8 and 9 are connected to the left hand windings of the repeating coil R² for the purpose of controlling the connector C over the trunk line 3. The connector C may be briefly described as consisting of a pair of wipers and their associated bank contacts, together with a stepping magnet for advancing the switch wipers and a release magnet for restoring the switch to normal. The mechanical construction of the connector C is somewhat similar to the well known minor switch but the circuits have been modified in accordance with the present invention.

Associated with the connector C and connected to the respective bank contacts in the banks of the connector there are shown three relays whose functions are to connect the ring and tip conductors of the plug P² to the secondary windings of the repeating coils R⁵ and R⁶ when energized. The plug P² is used by the operator at exchange No. 2 for completing toll calls to the local subscriber's lines such as indicated at A. Associated with the plug P² there is provided a ringing key RK for the purpose of enabling the operator to ring the called subscriber's bell. The subscriber's lines such as A are of the well known magneto type and terminate at exchange No. 2 in jacks such as jack J². Cord circuits (not shown) are used by the operator at exchange 2 for completing calls between local subscribers.

A cable comprising conductors 11 to 16, inclusive, extends from exchange No. 2 to the cable box for the purpose of operating the relays therein and to connect the primary windings of the repeating coils R⁵ and R⁶ to the through toll lines. The connections to the through toll lines are left normally open so as not to affect transmission, that is, if the primary windings of the repeating coils R⁵ and R⁶ were permanently connected in bridge of the toll lines the repeating coils as well as the cable capacity would greatly affect the talking transmission over the toll lines.

The exchange No. 2 being a small exchange and not constantly attended, a night key NK is provided for disconnecting the operator's head set and for connecting trunk line No. 3 to the tip and ring conductors of plug P² for a purpose to be described hereinafter.

Having described in a general way the layout of the system herein disclosed, the operation of the circuits will now be described in detail, it being assumed for this purpose that a subscriber in exchange No. 3, or beyond, 70 desires to converse with subscriber A in the small exchange, or exchange No. 2. It will further be assumed that an operator at exchange No. 3 has plugged into the jack J³ of the toll line 1 and has operated the drop D to 75 signal the toll operator at exchange 1 in the well known manner. The toll operator at exchange 1 inserts the answering plug of a cord circuit (not shown) into the jack J. Upon ascertaining that a connection is desired to 80 subscriber A in exchange 2, the toll operator at exchange 1 will insert the calling plug of the cord circuit into the jack J¹ and operate the dial key K and then dial the digit 1 by operating the calling device CD.

Responsive to the operation of the dial key K in exchange 1 a circuit for operating the line relay 23 of the connector C in exchange 2 may be traced as follows: from ground by way of lower winding of line relay 23, lower winding of impedance coil 22, conductor 9, upper left-hand winding of repeating coil R², trunk line No. 2, upper-right hand winding of the repeating coil R¹, impulse springs of the calling device CD, key K, lower right-hand winding of repeating coil R¹, trunk line No. 1, lower left-hand winding of repeating coil R², conductor 8, upper winding of impedance coil 22, to the upper winding of line relay 23 and battery. Line relay 23 energizes over the above traced circuit and closes a circuit for energizing the slow-to-release relay 24. Release relay 24, upon energizing, at armature 39 prepares the impulsing circuit and at armature 40 closes an energizing circuit for relay 21. At armatures 35 and 36 relay 21 shorts out the upper and lower windings of the impedance coil by connecting the upper and lower windings of the line relay direct to conductors 8 and 9. The impedance relay 22 is initially included in the circuits of the line relay 23 to prevent the battery and ground connections of the line relay from interfering with ringing current when the operator at exchange No. 1 desires to ring over trunk line No. 3. During impulsing, however, the impedance relay 22 is shorted out by the operation of relay 21 as before described.

Responsive to the operation of the calling device CD in accordance with the digit 1, the circuit of the line relay is interrupted and said relay in falling back closes a circuit for operating series relay 26 and stepping magnet 27 as follows: ground by way of armature 37 and its resting contact, armature 39 and its working contact, armature 41, winding of relay 26, and winding of stepping magnet 27 to battery. Series relay 26 and the stepping magnet 27 are operated over the 130

above traced circuit and the series relay 26 at armature 44 closes a circuit for maintaining the impulsing circuit independent of armature 41 of relay 25 in case said relay should energize. By the operation of the stepping magnet 27 the switch wipers 45 and 46 are stepped into engagement with the first bank contacts. After the impulse, relay 23 reenergizes and opens the impulsing circuit at armature 37. Relay 24 being slow-acting therefore maintains its armatures attracted between impulses. A short interval of time after the impulse the series relay 26, which is also slow to release deenergizes and at armature 43 closes circuits for energizing relays 20 and 25. The circuit for energizing relay 25 includes the switch wiper 46 and the multiply connected bank contacts of connector C and the circuit for energizing relay 20 includes the wiper 45 and the first bank contact. By the operation of relay 25 the impulsing circuit is opened at armature 41 and at armature 42 the release circuit of release magnet 28 is prepared. By the operation of relay 20 the talking conductors of trunk line No. 3 are disconnected at armatures 18 and 19 from the tip and ring conductors terminating in jack J^4 and are connected instead to the operator's headset through the normally closed springs of the night key NK.

The toll operator at exchange No. 1 now informs the operator at exchange No. 2 that a toll connection is desired with subscriber A whereupon the operator at exchange No. 2 inserts the plug P^2 into the jack J^2 associated with the line of subscriber A. The operator at exchange 2 operates the ring key RK associated with the plug P^2 thereby ringing the bell on the desired subscriber's line in the well known manner.

The toll operator at exchange No. 1 now releases the key K thereby opening the circuit of line relay 23. Line relay 23, upon deenergizing, opens the circuit of release relay 24 and the latter relay after an interval deenergizes. Release relay 24, upon deenergizing, at armature 38 opens the circuit of relay 20 and at armature 40 opens the circuit of relay 21 whereupon said relays deenergize. At armature 39 the release relay closes a circuit to release magnet 28 over a circuit including armatures 37, 39, and 42. By the operation of release magnet 28 the switch wipers 45 and 46 are returned to their normal positions.

In case the operator at exchange No. 2 has temporarily left her position and has not operated the night key NK the toll operator at exchange 1 releases the connector switch as previously explained and operates a ringing key in her cord circuit (not shown) whereupon the drop D^4 is operated in the well known manner. At armature 4 the drop D^4 closes a circuit for operating an alarm

signal in order to inform the operator at exchange 2 that a connection is desired.

The operator at exchange 2 upon hearing the alarm signal returns to her position and inserts the answering plug of a cord circuit (not shown) into the jack J^4 and converses with the distant operator in known manner after which she removes said plug and inserts the plug P^2 into jack J^2 if a connection is desired to subscriber A. The operator in exchange 2 now operates the ringing key RK and thereby ringing the bell on the called subscriber's line.

After giving the necessary instructions to the operator in exchange 2 the toll operator at exchange 1 again operates the key K thereby operating relays 23 and 24 as before. The toll operator now operates the calling device CD in accordance with the digits 2, 3, or 4 dependent upon which toll line is in use. In this case, as the toll line No. 1 is in use, the toll operator will dial the digit 2 whereupon the connector C is operated as previously described with the exception that relay 30 instead of relay 20 is operated when the series relay 26 deenergizes. The circuit for energizing relay 30 may be traced as follows: from ground by way of relay 33 in the cable box, conductor 12, winding of relay 30, second bank contact accessible to wiper 45 and said wiper, armature 38, and armature 43 to battery. Relay 33 also energizes over the above traced circuit and connects the primary windings of the repeating coil R^5 to the two conductors of the toll line No. 1. Relay 30, upon energizing, at armatures 47 and 48 connects the secondary windings of the repeating coil R^5 to the ring and tip conductors of the plug P^2 which are now in engagement with the line of subscriber A. At armature 49 relay 30 closes a locking circuit for itself and relay 33 which includes the plug seat contacts PS and the armature of relay 29. When the called subscriber answers the toll operator at exchange 1 converses with the called subscriber over toll line No. 1 by the aid of the repeating coils R and R^5 . The calling subscriber being already connected to toll line No. 1 the connection, therefore, between the calling and called subscribers is now completed and such subscribers may converse as desired. The established connection is supervised over the toll line No. 1 extending to the exchange No. 1 independent of trunk line 3.

When the desired connection is completed the toll operator at exchange No. 1 releases the key K whereupon the connector releases in the same manner as previously described. Relays 30 and 33, however, are maintained energized over their locking circuits and therefore do not deenergize when the connector releases.

When conversation is finished the toll operators at exchanges 1 and 3 remove the cord

circuits from the jacks J and J^3 . The toll operator at exchange No. 1 operates the key K and dials the digit 1 or rings the operator as previously described and tells her to remove plug P^2 from the jack of the called line. When the plug P^2 is returned to its plug seat the locking circuits of relays 30 and 33 are opened whereupon said relays de-energize to open the connections to the repeating coil R^5 . The toll operator at exchange 1 again releases the connector C and all apparatus used in establishing the connection is now in normal position.

Toll connections to toll line No. 2 are established in the same manner only the digit 3 is dialed instead of the digit 2 and relays 31 and 34 are operated to connect up the repeating coil R^6 to toll line No. 2. In case of a toll connection to the phantom circuit over toll line No. 3 the digit 4 is dialed whereupon relays 32, 33, and 34 are operated and establish a talking circuit to the phantom toll line in an obvious manner.

Toll calls originated at exchange No. 2 for exchange 3, or beyond, are handled in the following manner. A calling subscriber such as subscriber A desiring a toll connection operates his magneto at the substation thereby causing the drop D^2 to operate and signal the operator at exchange 2. The operator thereat inserts the plug of a cord circuit (not shown) into jack J^2 and when the operator learns that a toll connection, say to exchange 3, is desired she tells the party to hang up and that she will call back later. The operator at exchange 2 then inserts a calling plug of a cord circuit (not shown) into jack J^4 and rings down the drop D^1 to signal the operator at exchange 1 in known manner. The toll operator at exchange 1 answers by inserting the plug of a cord circuit (not shown) and after receipt of the information disconnects the plug from jack J^1 and plugs into an idle toll line or waits until one becomes idle. When an idle toll line is available the toll operator at exchange 1 plugs into such line and signals the toll operator at exchange 3. The operator at exchange 3 after receipt of the desired information extends the call to the desired subscriber's line. When the connection has been extended to the desired line the toll operator at exchange 1 is notified and she operates the key K and her calling device CD as previously described to connect with the operator's headset in exchange No. 2. The toll operator then informs the operator at exchange 2 that the connection is ready whereupon the operator at exchange 2 inserts the plug P^2 into the jack of the subscriber desiring the toll connection and rings the same. The toll operator at exchange 1 now releases key K thereby causing the connector C to release in the manner previously described. The toll operator now dials the digit 2, 3, or 4 dependent upon which of the toll lines is in

use. Responsive to dialing the proper digit the connector C is operated to energize the proper connecting relays whereupon the calling subscriber is connected direct to the through toll line in the same manner as previously described. 70

In case the size of the small exchange, or exchange No. 2, is large enough so that two toll connections between exchanges No. 2 and No. 3 are often desired at the same time a duplicate set of relays such as relays 20, 30, 31, 32, and 29 would be provided to be controlled from the sixth to the tenth bank contacts, respectively, of the connector C in the same manner as relays 20, 30, 31, are controlled. Another plug and ringing key similar to plug P^2 and ringing key RK would also be provided by means of which the connection to the subscriber's line is completed. The toll operator at exchange No. 1 would then dial the digits necessary to operate the desired relay or relays in the duplicate set in order to make the proper connections to the desired toll line. 75

Having described how toll connections are completed when the operator at the small exchange is on duty, a description will now be given of the method for completing toll calls when the operator is absent, for instance during the night. In order to provide some sort of service during her absence, the operator inserts the plug P^2 into the jack of some subscriber's line which may be, by way of example, the telephone line of the local drug store or some other pay station and then operates her night key NK before leaving her position. For convenience it will be assumed that substation A is used for night service. The toll operators are informed that after a certain time the small exchange is unattended and therefore when a toll call is extended to exchange 1 for a subscriber in exchange 2 the operation is as follows: The toll operator now operates the key K and then the calling device CD in accordance with the digit 1 thereby operating the connector C and relay 20 as previously described. The toll operator now connects ringing current to the trunk line No. 3 by means of a ringing key in a cord circuit (not shown). The ringing circuit is repeated through the repeating coils R^1 and R^2 in an obvious manner and extends by way of armatures 18 and 19 and their working contacts through the normally open springs controlled by the now operated night key NK , conductors 5 and 6, through the normally closed springs of the ringing key RK , tip and ring of plug P^2 , tip and ring conductors of the subscriber's line, and the bell of substation A. 90 95 100 105 110 115 120 125

When the subscriber A answers, the toll operator advises him who the call is for and if the call is for subscriber A or a party who can be immediately called to the phone the toll operator is advised of the fact. The toll 130

operator now releases relay 20 and connector C and then reoperates the connector C to connect the line of substation A to the through toll line in use in the same manner as previously described. However, in case the desired called party is located some distance from substation A and it will be some time before the called subscriber can reach substation A the toll operator is advised of the fact by subscriber A. Subscriber A hangs up his receiver and sends a messenger to inform the called subscriber that he is wanted at substation A to answer a toll call. The toll operator removes the plug of her cord circuit (not shown) from J¹ thereby bridging the drop D¹ across trunk line No. 3. The toll operator, however, in this instance does not release key K and therefore the connector C and relay 20 are maintained operated. When the desired called subscriber reaches substation A said subscriber manually operates the magneto at substation A thereby operating the drop D¹ at exchange No. 1. The toll operator, upon answering in known manner and ascertaining that the desired party is now at substation A, releases the key K, relay 20, and connector C and completes the desired connection as previously described. The connection now being completed the calling and called subscribers may converse with each other as desired.

When conversation is finished the toll operator at exchange No. 1 dials the digit 5 whereupon the connector operates as before described and closes a circuit for energizing relay 29 which may be traced as follows: from ground by way of the winding of relay 29, fifth bank contact accessible to wiper 45 and said wiper, armature 38, and armature 43 to battery. By the operation of relay 29 the locking circuit of relays 30-34, inclusive, is opened and the operated ones of said relays deenergize. The connector C is again released and all apparatus is returned to normal position.

Local connections between subscribers at exchange No. 2 are completed by the attendant or operator at such exchange by the aid of cord circuits (not shown) or by the calling subscriber ringing the code of the called subscriber when the desired called line is on the same line as the calling party. Connections between subscribers' lines in exchange No. 1 and exchange No. 2 are completed over the trunk lines No. 1 and No. 2 by the aid of cord circuits (not shown) in the well known manner and therefore need not be explained in detail.

Having described the invention, its utility and operation, what is considered new and is desired to have protected by Letters Patent will be set forth in the appended claims.

What is claimed is:

1. In a telephone system, three manual exchanges, through toll lines connecting said

first exchange and said third exchange, said toll lines passing close to but normally disconnected from said second exchange, a trunk line connecting said first exchange with said second exchange, and means whereby said trunk line is required to establish a particular toll connection between said second and third exchanges but is excluded from the talking circuit when the toll connection is completed, the talking circuit of the completed toll connection including inductive connections between the second exchange and a toll line at a point near said second exchange. 70

2. In a telephone system, three exchanges, through toll lines connecting said first exchange and said third exchange, said toll lines passing close to but normally disconnected from said second exchange, a trunk line connecting said first exchange with said second exchange, relays associated with said toll lines at a point near said second exchange for inductively connecting said toll lines to said second exchange, and means in said second exchange controlled over said trunk line at the will of the operator in said first exchange for energizing said relays. 80

3. In a telephone system, three exchanges, through toll lines connecting said first exchange and said third exchange, said toll lines passing close to but normally disconnected from said second exchange, a trunk line connecting said first exchange with said second exchange, relays associated with said toll lines at a point near said second exchange for inductively connecting said toll lines to branch lines terminating in said second exchange, a connector switch in said second exchange directly controlled over said trunk line at the will of the operator in said first exchange, means including a plug in said second exchange for completing a connection to a manual subscriber's line terminating therein, means for operating said connector to energize said relays, and other means also operated by said connector for inductively connecting said plug to said branch lines. 95

4. In a telephone system, three exchanges, through toll lines connecting said first exchange and said third exchange, said toll lines passing close to but normally disconnected from said second exchange, a trunk line connecting said first exchange with said second exchange, a manual subscriber's line terminating in said second exchange, means including a plug in said second exchange for connecting up said subscriber's line for night service, and means controlled at the will of the operator in said first exchange for signalling said subscriber over said trunk line and for inductively connecting said subscriber's line to a desired one of said toll lines at a point between said first and third exchanges. 115

5. In a telephone system, three exchanges, through toll lines connecting said first ex- 120

- change and said third exchange, said toll lines passing close to but normally disconnected from said second exchange, a trunk line connecting said first exchange with said 5 second exchange, a manual subscriber's line terminating in said second exchange, means including a plug in said second exchange for connecting up said subscriber's line for night service, means controlled at the will of the 10 operator in said first exchange for signalling said subscriber over said trunk line and for inductively connecting said subscriber's line to a desired one of said toll lines at a point between said first and third exchanges, means 15 independent of control from said first exchange for maintaining said inductive connection, and means controlled at the will of the operator at said first exchange for causing said inductive connection to be opened.
- 20 6. In a telephone system, three exchanges, through toll lines connecting said first and third exchanges, said toll lines passing close to but normally disconnected from said second exchange, a trunk line connecting said first exchange with said second exchange, and means controlled over said trunk line and at the will of the operator in the first exchange for causing said second exchange to be connected to any desired one of said 25 toll lines at a point near said second exchange.
- 30 7. In a telephone system, three exchanges, through toll lines connecting said first and third exchanges, said toll lines passing close to but normally disconnected from said second exchange, a trunk line connecting said first exchange with said second exchange, manual subscribers' lines terminating in said second exchange, and means controlled over said trunk line for causing a predetermined 35 one of said subscriber's lines to be connected and disconnected to and from any one of said toll lines at the will of the operator in the first exchange when said second exchange is unattended during the night.
- 40 8. In a telephone system, three exchanges, through toll lines connecting said first and third exchanges, said toll lines passing close to but normally disconnected from said second exchange, a plurality of relays in said 45 second exchange, each of said relays controlling circuits for inductively connecting one of the toll lines to said second exchange, a locking circuit for maintaining said relays when energized in operated position, and a 50 connector switch in said second exchange, said connector controlled over said trunk line by the operator in said first exchange to first, selectively operate one of said relays to inductively connect a desired one of said 55 toll lines to the second exchange at a point between the first and third exchanges, and second, to open the locking circuit of the operated relay in order to open the inductive 60 connections to the toll line.
- 65 9. In a telephone system, two physical toll

lines and one phantom toll line, a subscriber's line, a relay associated with each physical toll line, and means for selectively energizing either of said relays to inductively connect said subscriber's line to the respective physical toll lines or both of said relays to inductively connect said subscriber's line to said phantom toll line.

10. In a telephone system, three exchanges, through toll lines connecting said first exchange and said third exchange, said toll lines passing close to but normally disconnected from said second exchange, a trunk line connecting said first exchange with said second exchange, a connecting link in the second exchange, and means controlled by the operator in the first exchange over said trunk line for connecting said link with any one of said through toll lines.

11. In a telephone system, three exchanges, through toll lines connecting said first exchange and said third exchange, said toll lines passing close to but normally disconnected from said second exchange, a trunk line connecting said first exchange with said second exchange, a plug ending link circuit in the second exchange adapted to be connected with any subscriber's line in the second exchange, and means controlled by the operator in the first exchange over said trunk line for connecting said link circuit with any one of said through toll lines.

12. In a telephone system, three exchanges, through toll lines connecting said first exchange and said third exchange, said toll lines passing close to but normally disconnected from said second exchange, a trunk line connecting said first exchange with said second exchange, a connecting link in said second exchange, a plurality of relays, and means controlled by the operator in the first exchange over said trunk line for selectively operating desired combinations of said relays to inductively connect said link with any desired one of said through toll lines.

13. In a telephone system, a trunk line terminating in a line relay and a jack and drop, an impedance coil, a circuit for said line relay including said trunk line, said impedance coil, and said line relay in series, said impedance coil preventing said line relay from interfering with the operation of said drop when ringing current is applied to said trunk line, means for closing said circuit to operate said line relay, and means responsive to the operation of said line relay for short circuiting said impedance coil thereby directly connecting said line relay with said trunk line.

14. In a telephone system, a repeating coil, a trunk line terminating in said repeating coil, a jack and a drop normally connected to said repeating coil, a line relay, an impedance coil, a circuit for said line relay including said impedance coil, said repeating coil, and said line relay in series, said impedance

- coil preventing said line relay from interfering with the operation of said drop when ringing current is applied to said trunk line to operate said drop, means for closing said circuit to operate said line relay, and means 5 responsive to the operation of said line relay for short circuiting said impedance coil thereby by directly connecting said line relay with said repeating coil.
- 10 15. In a telephone system, three exchanges, toll lines connecting said first exchange and said third exchange, a toll trunk line connecting said first exchange and said second exchange, subscribers' lines terminating in 15 said second exchange, and means at said second exchange controlled over said trunk line at the will of the operator in the first exchange for connecting one of said subscribers' lines to a desired one of said toll lines for 20 talking purposes.
16. In a telephone system, three exchanges, toll lines connecting said first exchange and said third exchange, a trunk line connecting said first exchange and said second exchange, 25 subscribers' lines terminating in said second exchange, means at said second exchange controlled over said trunk line at the will of the operator in the first exchange for connecting one of said subscribers' lines to a de- 30 sired one of said toll lines for talking purposes, means for maintaining said connection independent of control from the operator, and means controlled at the will of the operator in the first exchange for opening 35 said connection.
17. In a telephone system, a trunk line terminating in a line relay, an impedance coil, a circuit for said line relay including said trunk line, said impedance coil, and said line 40 relay in series, said impedance coil rendering said line relay nonresponsive to ringing current when ringing current is applied to the trunk line, means for closing a circuit to operate the line relay, and means responsive 45 to the operation of said line relay for short circuiting said impedance coil thereby directly connecting said line relay with said trunk line.
18. In a telephone system, a first and a sec- 50 ond exchange, an interconnecting trunk line terminating at each exchange in an operator's switchboard, a branch at the second exchange connecting said trunk line to an automatic switch in that exchange, means at each 55 switchboard whereby the operator thereat may call the other operator over said trunk line, and means whereby said automatic switch may be controlled over two conductors of said trunk line in series from the 60 switchboard at the first exchange.
19. In a telephone system, two exchanges, a group of trunks comprising two physical trunks and a phantom trunk superimposed thereon connecting said exchanges and terminating in an operator's switchboard at 65
- each exchange, a branch of said phantom trunk terminating in an automatic switch at one exchange, and means at the other exchange for controlling the operation of said switch over said physical trunks in series. 70
20. In a telephone system, a trunk line, a signal at one end of said trunk line operative responsive to the application of alternating current to the other end of the trunk line, an automatic switch, a line relay bridged across the conductors of said trunk line at said one end thereof and responsive to direct current impulses sent over said trunk line for controlling the operation of said automatic switch, and means for substantially preventing the passage of alternating current through said line relay when such current is applied to said trunk line to operate said signal. 75
21. In combination with a two-way trunk line adapted to be signalled over by means of alternating current applied to either end, a relay bridged across the trunk in series with a source of direct current, and an impedance in the circuit of said relay for substantially preventing the passage of alternating current 80 through said relay when such current is applied to the trunk line. 85
22. In combination with a two-way trunk line adapted to be signalled over by means of alternating current applied to either end, a relay bridged across the trunk line and operative responsive to a flow of direct current over the trunk line, an impedance normally in the circuit of said relay for substantially preventing the passage of alternating current to said relay when such current is applied to the trunk line, and means controlled by said relay for excluding said impedance from its circuit. 90 95
23. In a telephone system, a trunk line terminating in a manual jack, an operator's circuit adapted to be manually connected with the trunk line by way of said jack for answering calls on the trunk line, and means controlled over the trunk line for automatically connecting said operator's circuit with the trunk line independent of said jack. 100 105
24. In a telephone system, a trunk line having two branches, one branch terminating in a manual jack and signal, the other branch terminating in an automatic switch, means controlled over the trunk line for operating either said signal or said switch, an operator's circuit adapted to be manually connected to said trunk line via said jack to answer calls on the trunk line, and means controlled by said switch for connecting said operator's circuit to the trunk line independent of said jack. 110 115
25. In a telephone system, three exchanges, through toll lines connecting the first and third exchanges, other toll lines connecting the first and second exchanges, a link circuit in the second exchange adapted to be manu- 120 125 130

ally connected with a subscriber's line, an automatic switch in the second exchange controlled from the first exchange over one of said other toll lines, and means controlled by said switch for connecting said link circuit with any one of said through toll lines.

26. In a telephone system, three exchanges, through trunk lines connecting the first and third exchanges, other trunk lines connecting the first and second exchanges, a link circuit in the second exchange adapted to be connected to a subscriber's line, an automatic switch in the second exchange, means for directly operating said switch over one of said other trunk lines to establish a connection between said link circuit and one of said through trunk lines, means for releasing the switch, and means in said link circuit for maintaining said connection intact after said switch is released.

27. In a telephone system, three exchanges, through trunk lines connecting the first and third exchanges, other trunk lines connecting the first and second exchanges, a link circuit in the second exchange adapted to be connected to a subscriber's line, an automatic switch in the second exchange, means for directly operating said switch over one of said other trunk lines to establish a connection between said link circuit and one of said through trunk lines, means for releasing the switch, locking means in said link circuit for maintaining said connection intact after said switch is released, and means for reoperating said switch to disable said locking means and to release said connection.

28. In a telephone system, three exchanges, through toll lines connecting the first and third exchanges, normally disconnected branches of said toll lines extending to said second exchange, trunk lines connecting the first and second exchanges, and means in the second exchange controlled from the first exchange over one of said trunk lines for establishing a connection between the second and third exchanges via one of said toll lines and the branch thereof without affecting the continuity of the toll line connected with.

29. A telephone system in which a first and a second exchange are connected by a trunk line terminating at each exchange in an operator's switchboard, and also in an automatic switch at the second exchange, in which the operators at the two exchanges may signal each other by applying alternating current to the trunk line, and in which the automatic switch is controlled by a line relay bridged across the conductors of said trunk line, characterized in that an impedance is included in the circuit of said line relay to prevent false operations of the line relay when alternating current is applied to said trunk line.

In witness whereof, I hereunto subscribe my name this 28th day of April, A. D., 1927.

VICTOR S. THARP.
